D7-341

EX

OR D 13,455

DESIGN FOR A STOVE.

Design No. 13,455, dated November 28, 1882

UNITED STATES PATENT OFFICE.

DESIGN FOR A STOVE.

SPECIFICATION forming part of Design No. 13,455, dated November 28, 1882,
Application filed October 24, 1882. Term of patent 7 years.

To all whom it may concern:

Be it known that we, H. CLAY BASCOM, a citizen of the United States, residing in the city of Troy, in the county of Rensselaer and State of New York, and TOBIAS S. HEISTER, a citizen of the United States, residing in the village of Lansingburg, in said county and State, have jointly invented and produced a new and original Design for Stoves, of which the following is a specification, reference being had to the accompanying cut, print, or engraving of a stove having said new design.

The design for the raised panel ornament A is composed of the two opposite straight up-right edge parts, a, two opposite straight inclined edge parts, b, and the two top and bottom convex edge parts, c, the inclined band d extending between said inclined edge parts and having the vine-form ornament e, the triangular grooved surfaces f, the top and bottom ornamental arcs, g g', and the upper and lower radially-ornamented segmental surfaces, h, all shaped and arranged together substantially as shown in the accompanying print.

The design for the outer portion of the oven-doors consists of the edge-molding i and the in-cut compound corner ornaments, j k l m, all shaped and arranged together so as to appear substantially as represented in the aforesaid cut.

The design for the large oven-door B consists of the central compound ornament, A, composed as above specified, in combination with the aforesaid outer ornaments, j k l m, all shaped and arranged together substantially as shown in the aforesaid engraving.

The design for the compound panel ornament C consists of the opposite upright and inclined straight edge parts a' b' and upper and lower convex edge parts, c', the inclined band d', having the ornament e', the triangular grooved surfaces f', and the upper and lower radially-ornamented quadrants, h', all shaped and arranged together substantially as shown in the aforesaid cut.

The design for the outer portion of the door D consists of the border molding i' and the in-

cut compound corner ornaments, j' k' l' m', all shaped and arranged substantially as shown in the aforesaid print.

The design for the door D consists of the compound center ornament, C, composed as above specified, and the outer ornaments, j' k' l' m', all shaped and arranged together substantially as shown in the aforesaid engraving.

The design for the panels E and F consists of the compound central ornament, n, outer molding i'', and intervening compound corner ornaments, o p q, all shaped and arranged together substantially as represented in the aforesaid print.

The design for the lower front door, G, consists of the oblong rectangular panel r, having the corner ornaments, s t, and the fluted-edge border molding i'', all shaped and arranged together substantially as shown in the aforesaid cut.

The design for the sides H of the supplemental base consists of the lower bead edge part, u, composed of straight, angular, concave, and convex united parts, the end ornaments, v, and the intermediate compound ornament w, all shaped and arranged substantially as shown in the accompanying engraving.

The design for the legs consists of the compound ornament x on the convex surface z and the upper corner ornaments, y, all shaped and arranged together substantially as shown in the aforesaid cut.

What we claim as our invention is—

1. The design for the panel ornament A, composed of the parts a b c d e f g g' h, shaped and arranged together as described.
2. The design for the outer portion of the oven-door, composed of the parts i j k l m, shaped and arranged together as set forth.
3. The design for the oven-doors, composed of the panel ornament A and outer ornaments, j k l m, all shaped and arranged together as set forth.
4. The design for the panel ornament C, composed of the parts a' b' c' d' e' f' h', shaped and arranged as described.

5. The design for the outer portion of the door D, consisting of the parts $i' j' k' l' m'$, all shaped and arranged as set forth.
6. The design for the door D, composed of the panel ornament C and outer ornaments, $j' k' l' m'$, all shaped and arranged together as set forth.
7. The design for the panels E F, composed of the parts $n o p q$, all shaped and arranged as set forth.
9. The design for the sides H of the supplemental base, composed of the parts $u v w$, ¹⁵ shaped and arranged as set forth.
10. The design for the legs, composed of the parts $x z y$, shaped and arranged as described.
- In testimony whereof we hereunto set our hands, in the presence of two subscribing witnesses, this 20th day of October, 1882.

H. CLAY BASCOM.
TOBIAS S. HEISTER.
